WHEEL

Friedrich H. Van Winsen, Kirchheim (Teck), Arthur Mahler, Fellbach, Wurttemberg, and Stefan Heiliger, Waiblingen, Germany, assignors to Daimler-Benz Aktiengesellschaft, Stuttgart-Unterturkheim, Germany

Filed Sept. 21, 1967, Ser. No. 8,676

Claims priority, application Germany Mar. 21, 1967

Term of patent 7 years

(Cl. D14—30)

FIG. 1

FIG. 2

FIG. 3

FIG. 4

FIGURE 1 is a front elevational view of a wheel for motor vehicles in accordance with our novel design;

FIGURE 2 is a perspective view taken from the front and toward the right thereof;

FIGURE 3 is an elevational view of the back side thereof; and

FIGURE 4 is a cross-sectional view thereof taken along line 4—4 of FIGURE 1.

The dominant features of our novel design are substantially shown in full lines.

We claim:

The ornamental design for a wheel, as shown and described.
